VALVE ACTUATING MECHANISM

Brian Wheeler, Beloit, Wis., assignor to Heisler
Locomotive Works, Erie, Pa., a corporation of
Pennsylvania

Application April 14, 1937, Serial No. 136,958

7 Claims. (Cl. 137—139)

In actuating valves, particularly throttle valves, it is desirable to be able to set the valve at various adjustments. The common way of accomplishing this is to operate the valve through a lever and to lock the lever by means of a pawl on the lever operated in connection with notches on a quadrant. This structure does not lend itself to fine adjustments of the valve and the present invention is designed to improve such a mechanism in this respect. Features and details of the invention will appear from the specification and claims.

A preferred embodiment of the invention is illustrated in the accompanying drawing as follows:

Fig. 1 shows a side elevation of a locomotive boiler and a throttle valve and actuating mechanism mounted thereon.

Fig. 2 a sectional view of the throttle valve.

Fig. 3 an enlarged view of the operating lever and the locking pawl.

Fig. 4 a section on the line 4—4 in Fig. 3.

1 marks a boiler, 2 a steam line leading from the boiler, 3 a throttle valve body connected with the steam line, and 4 a throttle valve head operating in the body. These parts are of ordinary construction. A rock arm 5 is mounted on a rock shaft 6. The shaft is journaled in a bearing, carried by the body 3, and extends through a stuffing box 6a on the wall of the boiler. A link 7 connects the rock arm 5 with the head 4. It can readily be seen that as the shaft 6 is rocked the head through the linkage may be opened and closed.

A rock arm 8 is arranged on the outer end of the shaft 6. A link 9 connects the rock arm 8 with an arm 10. The arm 10 is fixed on a shaft 11. The shaft 11 is journaled in a quadrant 12. The quadrant 12 is mounted on the side of the boiler. An operating lever 13 is fixed on the shaft 11 and arranged in position to be actuated for operating the throttle, a handle 14 being provided for its convenient operation. These parts so far as described may be of usual construction except the details of the quadrant.

45 The quadrant is provided with a peripheral groove, the walls of which are inclined toward each other in the direction of the bottom of the groove thus forming opposing wedging surfaces on the side walls. A pawl 16 having corresponding side walls operates in the groove. This pawl is carried by a rock arm 17 pivoted on a stud 18. The stud is mounted on the operating lever 13. An arm 19 extends from the arm 17, these arms forming a bell crank. The pawl 16

is moved into and out of the locking position in grooves by the swinging of this bell crank.

A latch bar 20 is pivotally connected by pin 21 with an arm 22 of a bell crank lever, the said lever having a companion arm 24. The bell crank lever is pivoted by means of a stud 23 on the operating lever 13. The lever has a latch handle 25 which is adapted to be grasped in connection with the handle 14. The latch bar has a pawl 26 which engages a stop 27 so as to lock the lever at the end of the quadrant and in the closed position of the valve. The latch bar has a slot 28 and a pin 29 extends through this slot and is secured in the arm 19. The slot is of just sufficient length to permit initial movement of the bar sufficiently to 15 release the latch 26 prior to engaging the pin 29.

A spring 30 is secured on a pin 30a on the latch bar 20 and a bracket 31 extending from the arm 19. This spring is of just sufficient strength to move the latch bar into locking position and hold 20 it there. A spring 32 has a supporting base 33, this base being the bottom of a housing 34 fixed on the operating rod 13. The free end of the spring is seated on the arm 19, the arm being provided with a projection 35 which extends into 25 the end of the spring.

To actuate the apparatus the operator grasps the handle 14 including the latch handle 25, withdraws the latch bar, overcoming the spring 30 in this action, and with a further movement of the 30 handle 25 and consequently the bell crank lever continues the movement of the latch bar after its engagement with the pin 29, and this final movement operating the rock arm 17—19 lifts the 35 wedge pawl 16 out of the groove thus freeing the operating lever from the quadrant. The operating lever can then be moved to exactly the desired adjustment for the valve. Upon the release of the handle the wedge pawl is returned to the 40 groove and through the friction incident to the wedging engagement securely locks the operating lever and holds the valve in the adjusted position. The end of the stop shoulder 27 and the end of the latch 26 have cam surfaces so that as 45 the operating lever is returned to closed position the latch bar automatically retracts so that the pawl 26 clears the stop and then snaps into locking position.

What I claim as new is:

1. In a valve actuating mechanism, the combination of a pivoted operating lever; a fixed quadrant; a setting latch, said quadrant and latch having wedging frictionally engaging surfaces of tongue and groove formation; and a 55

- locking latch positively locking the operating lever in closed position.
2. In a valve actuating mechanism, the combination of a pivoted operating lever; a fixed quadrant; a setting latch, said quadrant and latch having wedging frictionally engaging surfaces of tongue and groove formation; a locking latch positively locking the operating lever in closed position; and means for releasing said latches in sequence.
3. In a valve actuating mechanism the combination of a pivoted operating lever; a fixed quadrant; a setting latch, said quadrant and latch having wedging frictionally engaging surfaces of tongue and groove formation; a bell crank lever mounted on the operating lever carrying the setting latch; and means operating the bell crank lever.
4. In a valve actuating mechanism the combination of a pivoted operating lever; a fixed quadrant; a setting latch, said quadrant and latch having wedging frictionally engaging surfaces of tongue and groove formation; a bell crank lever mounted on the operating lever carrying the setting latch; a locking latch positively locking the operating lever in closed position; and means actuating the bell crank lever and the locking latch.
5. In a valve actuating mechanism, the combination of a pivoted operating lever; a fixed quadrant; a setting latch, said quadrant and latch having wedging frictionally engaging surfaces of tongue and groove formation; a bell crank lever pivoted on the operating lever carrying the setting latch; a locking pawl positively locking the operating lever in closed position; a latch bar carrying the locking pawl, said latch bar having a lost motion connection with the bell crank lever; and means actuating the latch bar.
6. In a valve actuating mechanism, the combination of a pivoted operating lever; a fixed quadrant; a setting latch, said quadrant and latch having wedging frictionally engaging surfaces of tongue and groove formation; a bell crank lever pivoted on the operating lever carrying the setting latch; a locking pawl positively locking the operating lever in closed position; a latch bar carrying the locking pawl, said latch bar having a lost motion connection with the bell crank lever; means actuating the latch bar comprising a rocking lever operable with the operating lever; and springs returning the latch bar and bell crank lever, and holding the latches in setting and locking positions.
7. In a valve actuating mechanism, the combination of a pivoted operating lever; a fixed quadrant; a setting latch, said quadrant and latch having wedging frictionally engaging surfaces of tongue and groove formation; a locking latch positively locking the operating lever in closed position; and a valve actuated by the mechanism and seated with the operating lever locked in closed position.

BRIAN WHEELER.
